UNITED STATES PATENT OFFICE.

CHARLES WILLIAM TOZER, OF LONDON, ENGLAND.

RETORT.

1,191,854.

Specification of Letters Patent.

Patented July 18, 1916.

Application filed March 15, 1915. Serial No. 14,518.

To all whom it may concern:

Be it known that I, CHARLES WILLIAM TOZER, a subject of the King of Great Britain, residing at London, England, have invented certain new and useful Improvements in Retorts for the Distillation, Carbonization, and the like of Coal and other Carbonaceous Materials, of which the following is a specification.

10 This invention relates to that class of retort for the distillation, carbonization, and the like, of coal and other carbonaceous materials constructed with a ring of chambers around a central axis each chamber being 15 approximately the same size, as shown in my British Patent No. 20158 of 1909; and, consists of an improved construction of such a retort whereby I can operate upon a larger quantity of carbonaceous material than is 20 now the case, each layer of carbonaceous material being efficiently acted upon at one time to produce the desired result.

Retorts of the class mentioned are principally used in gas works, smokeless fuel and 25 other works or elsewhere, where coal, wood, shale or any other carbonaceous substances are treated in the retorts under atmospheric or other pressure or in a vacuum or partial 30 vacuum and at either a low or high temperature which may be between the limits of 300° centigrade to 1200° centigrade. These 35 retorts are capable of being used in either a vertical, oblique or horizontal position and can be made of various metals, refractory materials and substances.

According to my present invention, the retort is made with two or more rings of spaces concentrically or eccentrically arranged with regard to each other and about 40 a common axis, the spaces being formed from a number of ribs and walls and all of approximately the same cross sectional area. By this means, I am enabled to carbonize a larger quantity of the material than hitherto with absolute uniformity. Hitherto, it 45 has not been possible to carbonize or distil coal and other carbonaceous material in large quantities, to produce coke or fuel uniform in character, excepting at a very 50 high temperature, and a long time period for carbonizing, and where it is attempted to carbonize at a comparatively low temperature, the fuel is not uniform in character, and there is a large percentage of breeze or 55 fines owing to the outer layer being carbonized or over carbonized and the inner layer

being soft or only partially carbonized. That is to say, the percentage of volatile matter increases from a minimum at the outer portion to a maximum at the inner 60 portion or center. This variation is very detrimental to the success of a smokeless fuel, and my improvement not only produces a fuel absolutely uniform in character but it carbonizes the charge in a remarkably short 65 period of time, thus showing the enormous advantages of a retort of this description. One retort with twelve sections having combined a cross sectional area available for carbonization equivalent to a plain tube 25 70 inches in diameter, and capable of holding about half a ton of coal will carbonize that quantity in one twentieth the time necessary when using the ordinary plain tube retort of the equivalent diameter. 75

The annexed sheet of drawings illustrate three examples of carrying my invention into effect.

Figure 1 is a longitudinal elevation and Fig. 2 a section on the line Y. Y. of Fig. 1 80 of a retort constructed with twelve spaces *a* and a central passage *b*. Fig. 3 is a longitudinal sectional elevation and Fig. 4 a section on the line Z. Z. of Fig. 3 of a retort constructed with twenty spaces *a* and a central passage *b* for heating gases, such central passage being connected at near its top and bottom by passages *c*, *d* leading from outside the retort. Fig. 5 is a section of a retort showing the divisions eccentrically arranged around a passage *b*. 90

As before stated, the spaces *a* are concentrically or eccentrically arranged around the gas passage *b* and each space *a* in the retort is of the same superficial area in cross section; that is to say, each space will contain the same amount of material to be distilled or carbonized so that the heat of the furnace acts uniformly on all the material in each space and not to a greater extent 95 upon one as would be the case if the spaces were not of the same capacity.

The retorts are made of a size to suit the quantity of material to be treated at one time. With the construction shown at Fig. 1, if it is assumed that the collective spaces *a* equal an area equivalent to a plain tube 25 inches in diameter the same will be capable of treating about half a ton of material at one time, while if the combined spaces *a* shown in Figs. 3 and 4 equal a superficial area in cross section of a plain tube 32 inches 100 105 110

in diameter such a retort is capable of treating about 16 cwt. of material at one time.

The spaces *a* are formed by concentric or eccentric walls *e* and radial ribs *f*, and such walls *e* and ribs *f* are tapered or angled so that the spaces which reach from one end of the retort to the other are tapered with the larger part at one end of the retort, whereby an easy charging and discharging of the 10 retort can take place.

Suitable doors are provided at the ends of each retort so that the contents can be treated under atmospheric or other pressure or in a vacuum or partial vacuum as will be well 15 understood, and the process can be carried out continuously or intermittently.

Some of the ribs, preferably the two which run from the center to the outside of the retort in the same plane, may be provided with 20 a passage way *c*, *d*, at top and bottom of the retort (see Figs. 3 and 4) so as to admit the heating gases from the furnace to the central passage *b*, in such case the heating of the contents of the retort is greatly assisted. In 25 fact the time of heating the contents of a retort such as shown in Figs. 3 and 4 can be done in one thirtieth of the time required to heat the same quantity of material in a plain tubular retort having the same capacity.

30 What I claim is:—

1. A retort of the class described comprising a plurality of tubes arranged within each other about a common axis, and a plurality of ribs arranged to hold said tubes in

spaced relation to provide compartments in 35 which the material to be treated is placed, said retort being formed with passages extending from the inner tube to the outside of the retort for providing a heat circulation through the latter, substantially as and for 40 the purpose described.

2. A retort of the class described, comprising a plurality of tubes arranged within each other about a common axis, a plurality of ribs arranged to hold said tubes in spaced 45 relation from each other, certain of said ribs being formed with passages extending from the inner tube to the outside of the retort, said retort being adapted to be charged at one end and discharged at the other end 50 thereof.

3. In a retort of the class described comprising a plurality of tubes arranged within each other about a common axis, and a plurality of ribs arranged to hold said tubes in 55 spaced relation, certain of said ribs being formed with passages extending from the inner tube to the outside of the retort thereby providing a heat circulation through the 60 interior of the latter.

In testimony whereof I have hereunto set my hand in presence of two subscribing witnesses.

CHARLES WILLIAM TOZER.
